UNITED STATES PATENT OFFICE.

JAMES L. PARSONS, JR., OF WASHINGTON, DISTRICT OF COLUMBIA.

COMBINED DERRICK AND CONCRETE-MIXER.

No. 811,243.

Specification of Letters Patent.

Patented Jan. 30, 1906.

Application filed April 12, 1905. Serial No. 255,215.

To all whom it may concern:

Be it known that I, JAMES L. PARSONS, Jr., a citizen of the United States, residing at Washington, District of Columbia, have invented certain new and useful Improvements in a Combined Derrick and Concrete-Mixer, of which the following is a specification.

My invention relates to a combined derrick and concrete-mixer, and has for its object the provision of a device of the class described arranged to receive the sand, cement, water, and other material comprising the concrete and to thoroughly mix said material while it is being conveyed to the point at which it is to be used, thereby rendering it possible to take the raw material and deposit it as thoroughly-mixed concrete with but one handling.

A further object of the invention is to so arrange a rotative concrete-mixing receptacle in combination with a derrick that said receptacle will be prevented from twisting in a horizontal plane as the boom of the derrick is swung from point to point.

Further objects and advantages of the invention will be set forth in the detailed description which now follows.

In the accompanying drawings, Figure 1 is a perspective view of an ordinary jib-derrick having my improved concrete-mixer applied thereto, and Fig. 2 is a longitudinal vertical section of said receptacle.

Referring to the drawings, the numeral 5 represents a jib-derrick of ordinary construction and comprising the rotative mast 6, bull-wheel 7, to which motion is imparted by a cable 8, a jib 9, which is pivoted at 10 to a bracket 11, carried by mast 6, a bearing-cap 12, a bearing-pin 13, carried by said cap, a bearing-plate 14, in which pin 13 has its bearing, guy-cables 15 for holding the mast in a vertical position, and sheaves 16 and 17, over which a jib-line 18 passes.

As has been hereinbefore stated, the foregoing elements comprise a derrick of ordinary construction; but while my improved concrete-mixer is well adapted to work in conjunction with such a derrick it is to be understood that any other form of derrick may be substituted therefor, if desired.

In carrying out the invention I provide a yoke 19, preferably constructed as shown, though any other form of yoke may be substituted therefor, if desired. Yoke 19 is swung, as at 20, to the outer end of jib 9 and carries sheaves 21 and 22, over which load-

lines 23 and 24 pass. The ends 23' 24' of said load-lines are secured to the blocks of sheaves 21 and 22, passing thence around grooved wheels 25 and 26, integral with a concrete-mixing receptacle 27, which will be hereinafter described. Said load-lines then pass over sheaves 21 and 22 rearwardly to a double sheave 26. Both of said lines and jib-line 18 then pass downwardly in the usual manner over pulleys 20' and through a central opening 6' of the mast and thence to any suitable source of power. The concrete-mixing receptacle 27 comprises a cylindrical shell 28, the ends of which are closed by flanges 29, which are cast integral with grooved wheels 25. A closure 30, hinged, as at 31, to shell 28 and provided with a latch 32, affords means for filling and emptying receptacle 27. It will be seen by referring to Fig. 1 that the load-lines pass entirely around grooved wheels 25. In other words, they are given at least one full turn thereon or more than one full turn, if that be found necessary. Diagonally-disposed blades 33 assist in the thorough mixing of the material when the receptacle 27 is rotated, as will presently be described.

The operation of the device is as follows: The material forming the constituent parts of concrete is placed in receptacle 27. It is apparent that in order to accomplish this said receptacle must rest nearly or quite upon the ground. Power is then applied to the usual drum of the hoisting-engine, (not shown,) upon which both of the load-lines are wound, to wind said lines upon said drum, and thereby simultaneously elevate and rotate the receptacle 27. This rotation of receptacle 27 causes the material contained therein to be thoroughly mixed. After receptacle 27 has been elevated to a sufficient height it may be swung to the point where it is desired to deposit the concrete by rotating the mast of the derrick in the usual manner. The lowering of receptacle 27 preparatory to dumping the concrete into the form prepared therefor causes said receptacle to rotate in the opposite direction, thereby further mixing its contents. By providing a yoke such as is herein shown and described and by having two load-lines passing over sheaves carried at the outer ends of said yoke receptacle 27 will be prevented from twisting in a horizontal plane as it is swung from point to point by derrick 5.

From the foregoing description it will be seen that means are herein provided for tak-

ing the raw material forming the constituent parts of concrete and depositing said material in the form of thoroughly-mixed concrete at any point within the radius of action of the derrick. By providing the device herein shown and descr'bed I am enabled to accomplish the foregoing object while handling the material but once.

While the elements herein shown and described are well adapted to serve the purposes for which they are intended, it is to be understood that my invention is not limited to the precise construction shown and changes may be made in the details thereof without departure from the invention.

Having thus described my invention, what I claim is—

1. The combination with a derrick having a movable boom; of a yoke secured directly to the outer end of said boom, sheaves carried upon the ends of said yoke and a load-carrying receptacle adapted to be simultaneously elevated and rotated by the load-lines of the derrick, said load-lines passing over the sheaves carried by the yoke.

2. The combination with a derrick having a movable boom, of a yoke secured directly to said boom adjacent the outer end thereof, sheaves carried by the outer ends of said yoke, load-lines passing over said sheaves and a receptacle having grooved wheels around which said load-lines pass.

3. The combination with a derrick comprising a mast capable of movement upon its axis and a boom carried by said mast and pivoted for vertical movement thereto, of a yoke secured directly to said boom adjacent the outer end thereof, load-lines, sheaves carried by the outer ends of the yoke over which said load-lines pass and a receptacle with which said load-lines engage, in such manner as to be simultaneously rotated and moved in a vertical plane by said load-lines.

In testimony whereof I affix my signature in presence of two witnesses.

JAMES L. PARSONS, JR.
